SMOKING PIPE

Clarence A. Pavey, Seattle, Wash.

Application April 7, 1939, Serial No. 266,449

10 Claims. (Cl. 131—198)

My invention has two general objectives in view—to the greatest degree possible to remove from the smoke, before it passes into the bore of the stem, and to deposit, those objectionable constituents of the smoke which are recognizable by their dark, apparently tarry nature and by their bitter taste; and to cool down the smoke so that it will not produce an impression of heat upon the tongue or the lining of the mouth, 5 throat, and nasal passages, so that it will not, in normal smokers' language, "bite the tongue."

The above objectives have had the attention of others, but still have not been achieved to the fullest degree possible. Previous attempts 10 have sometimes produced structures that are not sufficiently rugged; others may have been theoretically advantageous, but in use may be found to clog up with baked deposits, or to require excessive cleaning (to which they may be ill-adapted), or to block with condensation products essential air passages, thereby making the pipe gurgle and requiring excessive draft or "pull" to get the smoke through, and in so doing entraining the deleterious substances they are 15 intended to eliminate. Such prior devices have, in some instances, required undue care and skill in filling and handling the pipe while smoking, more than a careless or even a careful smoker will give, for no smoker feels satisfied with a 20 pipe that requires assiduous attention or skill. In other instances they may cause the tobacco to burn more in one part of the bowl than in other parts—for instance, to burn rapidly down the axis of the bowl, leaving a surrounding shell 25 of unburned tobacco which must be broken away and tamped down frequently. Again, in some former structures, and due to devices intended to accomplish one or both the above objectives, the tobacco does not burn entirely to the bottom 30 of the bowl, the condensation products are trapped and collect in the bottom of the bowl, and a moist, foul "heel" is left in the bottom.

It is, accordingly, one of the objects of the present invention to provide a construction which 35 will achieve the principal objectives, but by constructions which eliminate the drawbacks and disadvantages just referred to above.

More particularly it is an object of the present invention to provide a bowl for the pipe 40 which to all appearances, both externally and internally, and which for all practical purposes in use, is a normal bowl of a smoking pipe, which will contain an adequate charge of tobacco, which will cause that tobacco to burn evenly and 45 entirely to the bottom of the bowl, which will

prevent any collection of moisture within the bowl, but which is so constructed that the bowl 5 may be removed to clean the pipe, either to remove the objectionable condensation products, or to cut away the cake which might otherwise tend to accumulate in the bowl, and particularly in the bottom of the bowl.

It is emphasized that it is an important object of the invention to provide such a pipe in which the deposit of moist substances can not well occur within the bowl, so that it is scarcely possible to leave in the bottom of the bowl any damp heel of unburned tobacco, and hence the bowl will at all times be kept dry and sweet, and the entire charge of tobacco can be fully consumed.

It is a further object to provide a construction for smoking pipes in which all the liquid or liquefiable condensation products are directed 10 radially outwardly from and all about the periphery of the bottom of the bowl, and are deposited, by the act of smoking the pipe, upon the side walls of a cup which is separate from and below the bowl, which can be freely opened for 15 cleaning. Preferably they are deposited upon an absorptive liner which can be inserted within such a cup, and this liner, when it has absorbed or received a sufficient deposit of such liquid condensation products, can be removed and replaced with a fresh liner, thereby carrying with 20 it all the objectionable ingredients, and leaving the cup itself clean and sweet.

It is a further object to provide a construction of pipe in which there is a chamber beneath the bottom of the bowl itself, in which chamber, by 25 the draft or "pull" of the smoker on the pipe, there is produced a slight vacuum or minus pressure, thereby tending to draw air downward uniformly through the tobacco in the bowl, but not directly downwardly into this chamber, and whereby, in the normal case, a draft of fresh air from the exterior, but insufficient to affect 30 materially the draft through the tobacco, is drawn into this chamber, thereby to cool down the temperature within the chamber, and by this reduction of temperature to affect the condensation and deposition on the walls of the condensable liquid constituents of the smoke. It is 35 an object in conjunction with the above object to prevent intermingling of the smoke and of the exterior air thus drawn into the chamber, by maintaining them at different levels, and in this way to avoid interference with the draft by the indrawn air from the exterior.

Still a further object is to provide a pipe of 40

the general character indicated, which shall be strongly built; the parts whereof, some of which are removable, may be fitted together without difficulty; which is readily cleaned; and which 5 will properly lend itself to the accomplishment of the above objects.

My invention comprises the novel parts and the novel combination and arrangement thereof, as shown in the accompanying drawing, de- 10 scribed in this specification, and as will be more particularly defined by the claims which terminate the same.

In the accompanying drawing I have shown my invention embodied in a form which is at 15 present preferred by me, it being understood that various changes may be made in the form, character, and relative arrangement of the parts, without departure from the invention as claimed.

Figure 1 is a vertical section, axially of the 20 bowl and of the stem, illustrating my invention.

Figure 2 is a vertical section, substantially on the line 2—2 of Figure 1, and Figure 3 is a horizontal section substantially on the line 3—3 of Figure 1.

25 Figure 4 is a sectional view in perspective, illustrating the principles of my invention.

The bit of the pipe may be of any desired construction, and is not illustrated. The stem 19, with its usual bore 11, is likewise of normal construction. The stem terminates in a cup 1, which externally is of the usual appearance of the lower part of the bowl of a pipe. It is preferred, however, that its walls be relatively thin, and that they be substantially cylindrical. The 30 cup 1 may, but preferably does not extend upwardly as high as the normal bowl of a pipe. Its interior, therefore, is readily accessible for cleaning, and for removal and replacement of a liner, later referred to.

40 Fitted within the top of the cup 1 is a bowl 2. For the sake of appearance, if the cup does not completely enclose the bowl 2, the exterior of the bowl should be a smooth continuation of the cup 1, so that there is no appreciable break between the two. This may be achieved, and the position of the bowl within the cup may be precisely determined, by providing a shoulder 23 upon the bowl, between its top and bottom, which seats upon the rim of the cup. Preferably the cup and bowl are provided with indices (not shown) that may be brought into registry, to position the bowl properly within the cup, for reasons which will appear hereafter.

50 Interiorly the bowl 2 is substantially cylindrical, as indicated by its bore 21, though this bore may taper somewhat, as is usually the case. The bottom 23 of the bowl has its upper surface, indicated at 22, preferably plane and flat. The under surface of the bottom 23 is spaced above the bottom of the cup 1 to leave a chamber 3 between them, the proper spacing being determined by the seating of the shoulder 20 upon the lip of the cup, or by other suitable means. The exterior of the inserted part of the bowl is 55 cylindrical, as shown at 27, and the corresponding part of the interior of the cup is similarly formed.

The bottom 23 of the bowl is imperforate, so that no smoke nor draft may go directly downwardly, and so that no apertures are positioned in line with pressure in tamping the pipe, thereby to be clogged by tobacco. Smoke outlets are provided at the side of the bottom of the bowl, directly outwardly. These outlets are preferably 70 arranged substantially entirely about the peri-

phere of the bottom of the bowl. To this end slots 24 may be cut in the side wall of the bowl, beginning at the level of the bottom surface 22, and removing the side wall material thereabove for a short distance, leaving the bottom supported from the remainder of the bowl by pillars or posts 25. Preferably only two such posts are left, one of which is opposite the stem's bore 11, and the other of which may be located immediately above the stem. 10

These laterally directed, nearly semi-circular slots 24 constitute smoke outlets from the bowl 2, and by recessing or shouldering the exterior of the bowl, at the level of the top edge of the slots 24, as indicated at 29, or by cutting back the 15 edge 26 of the bowl's bottom 23, this edge 26 at all points extends outwardly beyond an extension of the inner wall 21 of the bore of the bowl, thereby to direct the smoke outwardly, rather than downwardly, and against the wall of the cup 1, 20 as is indicated by the arrows B. The recession of the edge 26 leaves a space clear for the escape of smoke radially in all directions from the smoke outlets 24. Below the edge 26 the bottom 23 is preferably beveled off, as indicated at 28, where- 25 by the smoke, after having impinged on the side walls of the cup 1, is directed downwardly and inwardly towards the center of the chamber 3, as indicated by the arrow C.

It may be pointed out here that this directional 30 movement of the smoke is caused by the production of a vacuum within the chamber 3, by drawing through the bore 11 of the stem. The whole chamber 3 is under reduced pressure. The air which is drawn in by this reduced pressure passes 35 downwardly into and through the tobacco in the bowl, as indicated by the arrows A; it is drawn downward substantially uniformly over the whole area of the burning crust, and if there is any departure from uniformity in this regard, it is in 40 the direction of affording stronger draft adjacent the side walls of the bowl, whereas normally the draft is weakest here. Direct draft towards the entrance to the bore 11 is obstructed by the imperforate bottom 23, and by the narrow annular 45 smoke passage between the edge 26 and the walls of the cup. The smoke, then, tends to escape laterally from the smoke outlets 24, and radially in all directions, as indicated by the arrows B, and thus enters the chamber 3 indi- 50 rectly, and with an abrupt change of direction, indicated by comparison of the arrows B and C, which in itself assists in the deposition of liquid constituents of the smoke. It tends to fill the whole chamber 3, rather than to be drawn too 55 strongly towards the bore 11. The reduced pressure within the chamber 3, as well as the lateral discharge and the abrupt change of direction, tends to lower the dew point, as it were, and thus per se effects condensation and deposition within 60 the chamber.

The pillars 25 tend to obstruct the escape of smoke from the pipe but little, the more especially as they are narrow on their inner face.

Should any liquid matter tend to deposit on the 65 surface 22, it will tend to run out by gravity into the chamber 3, since there is no marginal lip about the smoke outlets. Moreover, the hot smoke will act upon such liquid, tending to volatilize it and to entrain it, as the smoke passes 70 out through the outlets 24. As a result the surface 22 is always dry, clean, and sweet, except it may tend to cake with carbonized material. One reason that the heel of an ordinary pipe becomes moist is that there is no place for the moisture 75

to go, if it is not to be drawn into the mouth, so it collects at the lowest point of the bowl.

It is desired to cool down the smoke, and by this cooling further to effect deposition of the condensable liquids in the smoke, and to do this by means which will not too greatly lower the vacuum within the chamber 3, nor affect the drawing power of the pipe as a whole. Consequently, to this end I provide a breather aperture

10 14, admitting from the exterior into the chamber 3, of small size as compared to the size of the bore 11. In order that the air thus admitted, which cools down the temperature within the chamber 3, may not on the one hand affect the 15 smoke at the points where the smoke passes from the bowl, and may not on the other hand pass directly towards the bore 11, but will be diffused throughout the chamber 3, it is preferred that this aperture 14 be so located that the air 20 entering through it will impinge upon one of the pillars 25, and it is to locate this pillar properly that the index marks referred to above are provided to position the removable bowl 2. Air entering at 14 is then deflected by the beveled 25 surface 28, as is indicated by the arrow D to a level below the level of the smoke outlets 24, and into the chamber 3. Thus it diffuses throughout the chamber, and mingles with the smoke, but only after the smoke has entered the chamber 3, 30 and after it has impinged upon the walls of the cup 1 and has been deflected downwardly as indicated by the arrows C. The smoke indicated by the arrows C and the cool air, as indicated by the arrow D, mingle in the chamber 3, and the cool 35 air causes further condensation of condensable substances in the smoke and further cools down the smoke, without being sufficient in quantity, however, as to be noticeable or to noticeably lessen the draft, and the liquids thus condensed are 40 deposited upon the bottom of the cup 1. The mingled smoke and cool air pass out through the stem's bore 11, as indicated by the arrow E.

It will be particularly noted that the opening 14 for admission of cool air does not admit directly into the bowl wherein the tobacco is burning. The tobacco is only subjected to the downwardly drawn air, indicated by the arrows A, which must pass through the burning crust, and the cool air, admitted after the smoke has left 50 the bowl 2, can not possibly interrupt the burning of the tobacco. This cool air is so controlled and directed that it can have no effect until after the smoke has been drawn into the minus pressure chamber 3, clear of the tobacco, and as condensation proceeds the products thereof have no 55 chance to deposit within the bowl itself, but all condensation and deposition of liquid must take place only within the chamber 3.

The chamber 3 would tend to become foul from 60 condensation products if no means to dispose of them were provided, but I prefer to provide a removable liner 4, which fits within the cup 1, and which extends upward along the side walls of the cup, at least far enough to be impinged by 65 the smoke as it is directed at B laterally and radially from the outlets 24. It has been found that a great deal of the condensation takes place at this point by the abrupt change of direction and that the condensation products are deposited 70 at this level upon the liner 4, the smoke continuing on downward, as indicated by the arrows C. Of course, some further condensation takes place within the chamber 3, by reason of the cooling draft D, and such condensation is 75 deposited upon the bottom of the liner 4 within the

cup. Also any condensation that tends to remain liquid and to run, runs down the walls of the cup and its liner, to come to rest upon the bottom of the liner. This liner is preferably of absorptive material, such as blotting paper. I 5 have discovered that blotting paper imparts a disagreeable taste to the smoke unless treated, but I have found that if the blotting paper is first boiled in or impregnated with coffee, this objectionable taste is eliminated, and is replaced 10 either by a neutral taste or by a slightly pleasant taste.

It will be noted that the liner preferably extends upwardly to the upper limit of the cup 1, so that it lies between the cylindrical portion 21 15 of the bowl and the inside wall of the cup. The wooden bowl and cup cannot well be made to fit with great accuracy, hence the liner, being somewhat compressible, accommodates and compensates for any minor lack of accuracy in either the 20 cup or the bowl, where they interfit, and forms a tight joint, which is yieldable under the influences of temperature changes and the like. Proper holes are left in it to register with the opening 14 and with the bore 11. The liner is 25 readily removable and replaceable whenever it becomes fouled.

It should be noted that one of the pillars 25 is located immediately above the stem bore 11, and the advantage of this is that the smoke 30 passing from the smoke outlets 24 may not be drawn downwardly by the stronger draft through the bore 11, but must pass outwardly to either side of the bore for impingement and deposition upon the walls of the cup, before it can enter the 35 bore 11. Similarly the aperture 14 is preferably directly opposite the bore 11, and is shielded by a pillar 25 to cause diffusion by deflection downwardly, and it is opposite the bore so that the air is drawn through the entire width of the chamber 3 to affect all the smoke that enters and passes through this chamber.

It should also be noted that while the smoke outlets 24 are shown as two nearly semicircular slots, they might be replaced by a different number 45 of slots or by numerous closely spaced outlets of lesser individual angular extent. However, when they are wide slots it is a simple matter to insert a knife blade through these slots, when the bowl 2 is removed, and thus to cut out 50 and remove or scrape away any carbon that may tend to deposit upon the bottom surface 22 of the bowl. In whatever manner the smoke outlets are formed, however, they are radially disposed, and directed laterally outwardly, and extend substantially uniformly about the entire periphery of the bottom of the bowl.

With the construction as described the pipe may be filled, tamped and packed to a normal degree and in a normal manner, and since the 60 bottom is imperforate and its edges are well outside the projection of the inside wall 21 of the bowl, it follows that the pressure on the tobacco at the top of the bowl cannot push the tobacco outwardly through the smoke outlets, for the 65 pressure is downwardly and the tobacco would have to move outwardly to leave by the outlets 24. If a tobacco is used which is not of too fine granules, that is, which is not too powdery, there is little likelihood that any tobacco will pass into 70 the chamber 3 through the smoke outlets 24. If any tobacco should find its way into the chamber 3, however, it can readily be removed by removing the bowl 2, and either knocking it out or lifting it out when the liner 4 is removed. The 75

bowl 2 may be removed while the pipe is being smoked, and no harm occurs, and the smoker can continue smoking the tobacco upon replacement of the bowl, provided, of course, it is not left out 5 so long that it is extinguished. The cup 1 is freely open when the bowl is removed, and can be thoroughly cleaned, as can also the bore 11 of the stem.

Further devices within the bore of the stem or 10 in conjunction with the bit, for condensation of the vaporized liquid substances, may be employed if desired, but it has been found wholly unnecessary to do so with a pipe thus constructed, as there appears to be no objectionable nor 15 condensable products left in the smoke which could be condensed by such devices, even assuming that such devices are satisfactorily operable. The smoke which issues into the mouth of the smoker is cool and free from the objectionable, bitter- 20 tasting substances that are frequently found in pipe smoke, and the result is a thoroughly enjoyable and clean smoke, and a pipe that remains sweet and clean.

What I claim as my invention is:

23 1. A smoking pipe comprising a stem terminating in a cup, a bowl removably supported in the cup, with its bottom spaced above the bottom of the cup to leave a chamber therebetween, with which chamber the bore of the stem communicates, the bowl being approximately of hollow cylindrical shape, and its bottom being supported by spacer pillars, one of which is located directly opposite the stem's bore, the edge of the bottom thus spaced below the lower end of the bowl 30 proper, being disposed outwardly of the projection of the inner wall of the bowl, but being spaced inwardly from the outer wall of the bowl, to define wide, laterally directed and substantially circumferentially disposed smoke outlets, 35 the cup having a breather aperture admitting exterior air to impinge upon the pillar which is opposite the stem's bore, the exterior of the bowl being shaped to direct such breather air downwardly and across the chamber beneath the bowl's bottom, and an absorptive liner within the cup, and extending up the side walls to a level to 40 collect condensation from the smoke as it leaves the smoke outlets of the bowl and impinges upon the side walls of the cup, and as it is directed downwardly thence into the chamber.

45 2. A smoking pipe comprising a stem terminating in a cup, a bowl removably supported in the cup to dispose the underside of the bowl's bottom above the bottom of the cup, to leave a chamber therebetween, the stem's bore communicating with the chamber substantially at the cup's bottom, the bowl having circumferentially disposed smoke outlets directed laterally and unobstructedly towards the side walls of the cup, but spaced 50 therefrom to afford communication with the chamber, the upper side of the bowl's bottom being so disposed and arranged that no part is lower than the outer edge of the smoke outlets, to avoid entrapment of liquid within the bowl and to facilitate its lateral discharge, with the natural draft, against the side walls of the cup.

55 3. A smoking pipe comprising a stem terminating in a cup, a bowl removably supported in the cup, and having its outer wall closely embraced 60 by the cup, with the lower face of its bottom spaced above the bottom of the cup to leave a chamber therebetween, with which chamber the stem's bore directly communicates, the bowl's bottom being supported below the lower edge of the 65 bowl's side walls by spacer pillars, and the upper

face of the bowl's bottom extending outwardly beyond the inner surface, projected, of the bowl's side walls, to define with the lower edge of the bowl circumferentially disposed, laterally directed smoke outlets, the outer edge of the upper face 5 of the bowl's bottom being spaced inwardly from the outside surface of the bowl's side walls, and from the contiguous walls of the cup, to afford smoke passages admitting to the lower chamber.

4. A smoking pipe comprising a stem terminat- 10 ing in a cup, a bowl removably supported in the cup, with the lower face of its bottom spaced above the bottom of the cup to leave a chamber therebetween, with which chamber the stem's bore communicates, the upper surface of the bowl's 15 bottom being substantially level from edge to edge, and such edges being spaced below the lower edges of the bowl's side walls, and lying at least as far outwardly as the inside walls of the bowl, but terminating inwardly of the inner walls of 20 the cup, for communication with the chamber below, and the bowl's bottom being supported from and below the lower edge of its side walls by spacer pillars widely spaced circumferentially, to define smoke outlets from the bowl of sufficient height 25 and circumferential extent to afford convenient access to the bottom interior of the bowl, for removal of caked residue.

5. A smoking pipe comprising a stem terminat- 30 ing in a cup, a bowl removably supported in the cup, circumferentially spaced spacer means sup- 35 porting the bowl's bottom with its upper face spaced below the lower edge of its side walls, and its lower face spaced above the cup's bottom to leave a chamber therebetween, with which cham- 40 ber the stem's bore communicates, the edges of the upper face of the bowl's bottom, which are spaced below the lower edges of the bowl's side wall, lying at least as far outwardly as the inside walls of the bowl, projected, but terminating inwardly 45 of the inner walls of the cup, the lower face of the bowl's bottom being undercut from the edges of the bottom, the formation and arrangement of the bottom's faces and edges, relative to the cup and to the lower edges of the bowl's inside 50 walls, affording, first, circumferentially disposed smoke outlets from the bowl outwardly directed against the walls of the cup, and then downwardly directed smoke passages which have their greatest restriction past the outer edges of the bowl's bot- 55 tom, for most intense draft at that point.

6. A smoking pipe comprising a stem terminat- 60 ing in a cup, and a bowl removably supported in the cup, with its bottom spaced above the bottom of the cup to leave a chamber therebetween, with 65 which chamber the bore of the stem communicates, the bowl being approximately of hollow cylindrical shape, and its bottom being supported by spacer pillars, one of which is located directly opposite the stem's bore, the edge of the bottom thus spaced below the lower end of the bowl proper, being disposed outwardly of the projection of the inner wall of the bowl, but being spaced inwardly from the outer wall of the bowl, to define wide, laterally directed and substantially cir- 70 cumferentially disposed smoke outlets, the cup having a breather aperture admitting exterior air to impinge upon the pillar which is opposite the stem's bore, the exterior of the bowl being shaped to direct such breather air downwardly and across the chamber beneath the bowl's bottom.

7. A smoking pipe comprising a stem terminat- 75 ing in a cup, a bowl supported in the cup, with the edges of its bottom spaced inwardly from the side walls of the cup, and its bottom spaced below 75

its side walls and above the bottom of the cup, to leave a chamber between the bowl's bottom and the cup's bottom, with which chamber the bore of the stem communicates, and pillars extending between the side walls of the bowl and its bottom, together occupying a minor part of the periphery of the bowl's exterior and defining therebetween smoke outlets which constitute the major part of such periphery, and which are directed unobstructedly towards the side walls of the cup to discharge smoke thereupon, above the chamber, but communicating therewith about the inwardly spaced edges of the bottom.

8. A smoking pipe comprising a stem terminating in a cup, a bowl supported in the cup, with the edges of its bottom spaced inwardly from the side walls of the cup, and its bottom spaced below its side walls and above the bottom of the cup, to leave a chamber between the bowl's bottom and the cup's bottom, with which chamber the bore of the stem communicates, and pillars extending between the side walls of the bowl and its bottom, of generally trapezoidal shape to define a plurality of smoke outlet slots flaring from the inside of the bowl outward toward its exterior wall, of a combined extent to constitute the major part of the bowl's exterior periphery, the pillars occupying a minor part of such periphery, and affording communication between the interior of

the bowl and the cup's chamber beneath the bowl, for discharge thereto of smoke emerging through the slots.

9. A smoking pipe comprising a stem terminating in a cup, a bowl supported in the cup with its bottom spaced from the cup to leave a chamber therebetween, with which chamber the bore of the stem communicates, the side wall of the bowl adjacent its bottom being apertured around a major part of its exterior periphery, and the exterior aperture edges being spared from the inner wall of the cup, to afford passage for smoke from the bowl's interior through its apertured side wall to said chamber, and thence into said stem.

10. A smoking pipe comprising a stem terminating in a cup, a bowl supported in the cup with its bottom spaced from the cup to leave a chamber therebetween, with which chamber the bore of the stem communicates, the side wall of the bowl adjacent its bottom being apertured around a major part of its exterior periphery and flaringly from the inside of the bowl outward toward its exterior wall, and the exterior aperture edges being spaced from the inner wall of the cup, to afford passage for smoke from the bowl's interior through its apertured side wall to said chamber, and thence into said stem.

CLARENCE A. PAVEY.

CERTIFICATE OF CORRECTION.

Patent No. 2,235,847.

March 25, 1941.

CLARENCE A. PAVEY.

It is hereby certified that error appears in the printed specification of the above numbered patent requiring correction as follows: Page 5, second column, line 11, claim 9, for the word "spared" read --spaced--; and that the said Letters Patent should be read with this correction therein that the same may conform to the record of the case in the Patent Office.

Signed and sealed this 29th day of April, A. D. 1941.
